2 SHEETS—SHEET 2.

UNITED STATES PATENT OFFICE.

FRANK FRANZ, WALTER S. TOWER, AND ARCHIBALD H. WELLS, OF WALLACE, IDAHO.

ROCK-DRILL CHUCK.

1,081,527.

Specification of Letters Patent.

Patented Dec. 16, 1913.

Application filed December 9, 1912. Serial No. 735,787.

To all whom it may concern:

Be it known that we, FRANK FRANZ,
WALTER S. TOWER, and ARCHIBALD H.
WELLS, all residing at Wallace, in the
5 county of Shoshone and State of Idaho,
have invented certain new and useful Im-
provements in Rock-Drill Chucks, of which
the following is a specification.

Our invention has reference to chucks for
10 reciprocating rock drills and it primarily
has for its object to provide a simple, eco-
nomically and compactly made, and strong
device for clamping the bit in rigid connec-
tion with the reciprocating member of the
15 drilling apparatus, and in which the parts
are especially designed so that they auto-
matically become self tightening under the
impact force of the bit as it is hammered
into the surface to be drilled.

20 Another and important object of our in-
vention is to provide an improved means
for clamping the bit which includes a spe-
cial construction of gib engaging key and
the coengaging parts whereby the key while
25 operating under the impacting blows of the
drill to effect a positive clamping of the bit,
remains in such position, relatively to the
bit and the housing in which the bit clamp-
ing means is carried, that it can be quickly
30 loosened by a very slight tap on the end
thereof and which under continued drilling
operation does not become battered or de-
formed.

35 With other objects in view that will be
hereinafter apparent, our invention consists
in a rock drill chuck embodying the peculiar
construction and novel arrangement of
parts, hereinafter fully explained, specifi-
40 cally pointed out in the appended claims and
illustrated in the accompanying drawings,
in which:

Figure 1 is a perspective view of a drill
chuck embodying our invention. Fig. 2 is
a vertical longitudinal section of the same,
45 parts being inside elevation and shown in
their operative or bit clamping position.
Fig. 3 is a transverse section thereof on the
line 3—3 on Fig. 2. Fig. 4 is a longitudinal
section of the same, the parts being shown
50 shifted to illustrate the manner of assem-
bling the same for use. Fig. 5 is a perspective
view of the bearing or housing end of the sleeve,
the housing being shown as a separate member.
Fig. 6 is a perspec-
55 tive view of the gib, the key, the sleeve and
the bit socket members separated. Fig. 7 is

a detail view of a slightly modified form of
the sleeve or housing hereinafter referred to.

In the drawing, is shown a practical em-
bodyment of our invention, and the same in-
cludes a member 1, provided with a stop
60 collar 10, and which forms a part of the re-
ciprocating plunger of the drill mechanism.
The outer end of member 1 has a long socket
2 containing the bushing 3 in which is re-
ceived the drill bit 4, the said bushing and
65 the socketed end of the member 1 having alin-
ing elongated and longitudinally extending
slots 5—6 that receive the gib 7 whose upper
edge is concaved to snugly engage the bit
70 shank, and whose upper end is rearwardly
inclined, as shown.

8 designates a sleeve that is slidably
mounted upon the member 1 and it is held
for a limited movement on the said member
1 by the shoulder 10. Sleeve 8 has a radial
extension 81 formed with a wedge shaped
75 longitudinal slot or housing 82, the top or
clamping surface of which inclines rear-
wardly. The lower part of the sleeve 8 is
made thicker than its sides whereby to in-
crease the weight of the said lower part of
80 the sleeve to off-set the weight of the keys,
spring housing, and the main housing 82,
and thereby balance the weight of the pis-
ton, relatively to its axis, and in consequence
85 help the ratcheting motion of the piston
when at work.

9 designates a supplement housing
mounted on the inner or rear edge of the ex-
90 tension 81 and the said housing may be a
separate member and secured to the said ex-
tension 81 by means of lugs 91 on the said
housing adapted for lapping over the exten-
sion 81 and for engaging seats 83 in the
95 housing in which they are held by screws 12.
Instead of the housing being an attached
part of the extension 81, it may be formed
integral, as shown in Fig. 7.

11 designates what we term the gib key,
100 which, in practice, is a short tapering or
wedge shaped bar, the upper face 20 of
which is rounded to engage the correspond-
ingly round clamping face 21 of the housing
82. It should be here stated that the taper
105 of the gib key 11 is on the upper face and
the said taper or incline and the co-engaging
incline or taper surface of the housing are
of different planes, the taper of the key 11
in the practical arrangement of our inven-
110 tion being one and seven-eighths of an inch
to the foot while the face 21 of the sleeve is

tapered one and one-half inches per foot. By reason of the difference in the taper of the wedge faces of the housing surface 21 and the key surface 20, the latter, when 5 placed on top of the gib 7, as shown, makes up the required taper in the wedge shaped slot, of one and one-half inches per foot, that is to say, both keys, the gib 7 and the key member 11, when placed together, make 10 up a taper of one and one-half inches to the foot.

15 designates a stout coil spring that is supported within the housing 9, one end of which is mounted upon a boss or rivet 16, 15 formed on the housing, and the other end seats in a socket 17 in the adjacent end of the key 11. The key 11 has lateral extensions 12—13, at its opposite ends, the extensions 13 serving the purpose of keeping the tension 20 on the spring 15 and also for preventing the key going too far forward, whereas the extensions 12 on the other or smaller end of the key serve to protect the spring 15 from too much recoil when the key 11 is 25 driven back by tapping the outer end thereof, as the said extensions, should the key be struck with excess force will engage the front face of the housing.

By reason of the peculiar construction and 30 combination of parts as described and shown the key is always held up to its operative or wedging position by the spring 15 and further by reason of such positioning of the key when the sleeve 8 is impelled forwardly 35 by the force of the drill striking the rock, the wedge of the key 11 between the sleeve and the gib is uniform and such that the gib is positively forced down to the desired creeping action with respect to the drill.

40 From the foregoing taken in connection with the drawing, it is believed that the complete construction, the manner of its use

and the advantages of our invention will be readily understood by those skilled in the art.

What we claim is:—

1. A drill chuck comprising a bit receiving body having a longitudinal slot in the bit holding end, a bit engaging gib having a rearwardly inclined upper wedging face, a sleeve slideable upon the bit holding body, and including a socket portion having an inclined wedging face that inclines in the same direction as the wedge face of the gib, a wedge key that tapers from the inner to 55 toward the outer end adapted for fitting in the socket for engaging the gib and the wedge face of the socket.

2. A drill chuck comprising a bit receiving body having a longitudinal slot in the 60 bit holding end, a bit engaging gib held in the said slot, the said gib having a rearwardly inclined upper face, a sleeve slideable on the bit holding body and including a main socket portion having an inclined bearing surface, a key having the cross sectional shape of the space between the inclined faces of the sleeve and the gib, the said key being 65 endwise insertible in the said space for engaging the inclined surfaces of the gib and 70 the sleeve bearing surfaces, a socket member mounted on said sleeve and in communication with the wedge space of the same, and a spring held within said socket member and 75 engaging said key at its inner end to continuously tend to push said key to its wedging position, said key having a recess to receive the end of said spring.

FRANK FRANZ.
